UNITED STATES PATENT OFFICE.

J WILLIAM WARREN, OF KANSAS CITY, MISSOURI.

ADZING-MACHINE FOR RAILROAD CROSS-TIES.

1,300,064.

Specification of Letters Patent.

Patented Apr. 8, 1919.

Application filed June 8, 1918. Serial No. 238,910.

To all whom it may concern:

Be it known that I, J WILLIAM WARREN, a citizen of the United States, residing at Kansas City, in the county of Jackson and 5 State of Missouri, have invented new and useful Improvements in Adzing-Machines for Railroad Cross-Ties, of which the following is a specification.

In the maintenance of railway road-beds 10 it has been found in practice that after the rails have been laid for a time, the weight and pressure of the trains upon the rails causes the latter to sink into the surfaces of the cross ties more at the outer edges 15 of the rail foot than at the inner edges so that the rails are inclined slightly outward toward their tread portions, and it is the object of this invention to provide a simple and relatively inexpensive machine which 20 may be used readily by steel gangs and repair men in correcting this evil by providing rail seats in the ties which will serve rather to cause an inward inclination of the rails toward their tread portions, said machine 25 being such as to be readily moved along the track from tie to tie and operated with a minimum of effort and an accuracy in the formation of the rail seat without calling for any special mechanical skill on the part 30 of the operator.

Further objects and advantages will appear in the course of the following description, it being understood that changes in 35 form, proportion and details may be resorted to, within the scope of the appended claims, without departing from the spirit of the invention.

In the drawings:

Figure 1 is a plan view of a machine embodying the invention.

Fig. 2 is a front view of the same.

Fig. 3 is a side view.

Fig. 4 is a sectional view of a portion of the front end of the machine upon the plane 45 indicated by the line 4—4 of Fig. 1.

Fig. 5 is a similar sectional view on the plane indicated by the line 5—5 of Fig. 4.

Figs. 6 and 7 are detailed side and edge views of a cutter disk.

Fig. 8 is a view of a cross tie showing at A the form of seat which is produced by a machine constructed in accordance with this invention, and at B showing the depressions which are ordinarily formed in a cross tie by the pressure of a track rail and which by reason of declining outwardly causes an

outward inclination of the rail toward its tread portion.

The illustrated machine consists essentially of a main or supporting frame having 60 side beams 10 and cross beams 11 upon which is erected an upright frame 12 having standards 13, cross bars, 14, and spacers 15, said frame being provided at one end with flanged supporting wheels 16 adapted to 65 traverse the track rail at one side of the road-bed and provided at the other end with guide rolls 17 for traversing a track rail or any other suitable support at the other side of the road-bed. The cutter 18 which is in 70 general construction of trunco-conical form is carried by a shaft 19 mounted in suitable bearings upon the cross beams of the frame and having a pulley 20 through which motion is communicated to the shaft from an 75 engine 21 (gas or other motive power being suitable in this construction,) by means of a belt 22. Preferably the cutter consists of a plurality of disks 23 having undercut peripheral teeth provided with diagonal cutting edges as shown in detailed Figs. 6 80 and 7.

The guide rolls 17, of which a plurality may and preferably should be employed, are mounted in a carrier frame 23' having 85 a central yoke 24 to pass over and avoid interference with the cutter wheel, and said carrier frame is adjustable vertically with reference to the main supporting frame, so as to raise or lower the cutter wheel to produce the desired depth of cut or seat in the cross tie upon which the same is operating. In the construction illustrated this adjustment is effected by means of adjusting 90 screws 25 provided at their upper ends with hand wheels 26 and engaging nuts 27 which are carried by said carrier frame, the lower extremities of the adjusting bolts being swiveled by means of suitable gear 28 in the main or supporting frame.

In operation, the frame is disposed with the flanged wheels upon one rail of the track, and is moved along from tie to tie to successively bring the cutter into operative position with reference to the successive ties 105 which are thereby provided with inwardly declining seats inclined as at A, as shown in Fig. 8. The guide rolls 17 traverse a suitable support such as the cross ties at the opposite side of the road-bed from the 110 flanged wheels 16, and by means of the adjusting devices above described the depth of

the seats in the cross ties may be properly gaged to suit the condition, and if necessary the adjustment of the depth of the cutter may be effected from time to time in order 5 to properly and accurately bed the rails and thus avoid the auxiliary tamping which is frequently necessary in the operation of setting a rail.

It will be obvious moreover, from the foregoing description that a machine as indicated may be constructed at a comparatively small cost, and in the event of injury to one or another of the disks of the cutter, the injured disk may be removed and replaced 15 at small expense, and also the disk may be removed for the purpose of sharpening the teeth thereof.

What I claim is:—

- 20 1. A machine of the class described having a supporting frame provided at one end with flanged track rail traversing wheels and at the other end with supporting and guiding rolls, a rotary cross tie adzing tool mounted upon said frame at the end adjacent to said guiding rolls, means for operating said tool, and means for adjusting the supporting frame relative to said guiding rolls to vary the depth of the cut of said tool.
- 25 30 2. A machine of the class described having a supporting frame provided at one end with flanged rail traversing wheels, a guide frame arranged at the other end of the supporting frame and having guide rollers for traversing a stationary support, a rotary

adzing tool arranged at that end of the supporting frame adjacent to said guide frame, means for operating said tool, and adjusting devices for varying the vertical position of the guide frame with reference to said supporting frame to vary the depth of the cut 40 of the tool.

3. A machine of the class described having a main supporting frame provided at one end with rail traversing wheels, a guide 45 frame adjustably mounted for vertical movement at the opposite end of said supporting frame and provided with guide rollers for contact with a stationary support, and an adzing tool mounted upon the supporting frame, means for operating said tool, and adjusting devices for the carrier frame consisting of feed screws mounted in nuts on the guide frame and swiveled in said supporting frame for relatively moving 50 the carrier and supporting frame to vary the depth of the cut of said tool.

4. A machine of the class described having a frame and supporting means mounted thereon, the supporting means at one end of said frame being adjustable vertically to vary the elevation of the adjacent end of said frame, a trunco-conical adzing tool having its shaft mounted upon the frame and consisting of a plurality of disks provided 55 with peripheral cutting teeth for contact with the surface of a railroad cross tie, and means for operating the shaft of said tool.

In testimony whereof I affix my signature.

J. WILLIAM WARREN.
